(57) **CLAIM**

I claim the ornamental design for a cord adjuster, as shown and described.

DESCRIPTION

FIG. 1 is a bottom front perspective view of a cord adjuster according to my new design;

FIG. 2 is a front view of the cord adjuster shown in FIG. 1;

FIG. 3 is a rear view of the cord adjuster shown in FIG. 1;

FIG. 4 is a left side view of the cord adjuster shown in FIG. 1; FIG. 5 is a right side view of the cord adjuster shown in FIG. 1;

FIG. 6 is a top view of the cord adjuster shown in FIG. 1;

FIG. 7 is a bottom view of the cord adjuster shown in FIG. 1; and,

FIG. 8 is a bottom rear perspective view of the cord adjuster shown in FIG. 1.

The ornamental design which is claimed is shown in solid lines in the drawings.
